UNITED STATES PATENT OFFICE.

FRIEDRICH SCHWERD, OF FRANKFORT-ON-THE-MAIN, GERMANY.

DEVICE FOR AUTOMATICALLY ARRESTING THE FEED-MOTION IN GRINDING-MACHINES.

No. 920,869.

Specification of Letters Patent.

Patented May 4, 1909.

Application filed November 18, 1908. Serial No. 463,287.

To all whom it may concern:

Be it known that I, FRIEDRICH SCHWERD, head engineer, and resident of Im Trutz Frankfurt 18, Frankfort-on-the-Main, Kingdom of Prussia, German Empire, have invented new and useful Improvements in Devices for Automatically Arresting the Feed-Motion in Grinding-Machines, of which the following is a specification.

10 Instead of the devices formerly employed for arresting the feed motion of a grinding wheel or the like by releasing a spring, it has already been proposed to use a finger which is pressed elastically against the work and, as 15 soon as the latter has been ground to the desired extent, influences an electric contact that interrupts a quiescent current or completes a working current and thereby stops the feed. In one of these known arrangements the finger employed consists of a pivotally mounted long lever which lengthens considerably the movement of the feeler pin against the work, and thus causing the disadvantage that the unavoidable swinging 20 motion of the work is magnified in the same proportion so that the contacts are liable to be closed prematurely while at the same time the mounting of the lever on a rotating axis also results in inaccuracies. These defects are obviated in the subject of the present application by replacing the said lever by a bolt capable of rectilinear displacement in a guide, a contact-piece being fastened directly on to the bolt. The swinging movement cannot undergo any amplification and hence the highest degree of accuracy is attained with this device. The known devices of this kind are also attended with the defect that the only way to adjust the contacts is by 30 means of a standard piece of work or a templet, which has to be clamped between the feeler pin and the grinding wheel. Consequently it is impossible to grind any given piece of work to any desired predetermined 35 size. This possibility is afforded with the subject of the invention, inasmuch as the distance between the contacts can be adjusted with precision on the device itself, by means of micrometer screws, which carry the contacts and are fitted with graduated heads. This adjusting device can be applied both to the first contact, which influences the feed movement, and to the second contact, which 45 stops the machine altogether.

50 55 The drawing illustrates a typical example

of a device of this kind as a lateral elevation in partial section.

The bolt 1 is pressed by the spring 2 so that its outer terminal surface presses in a radial direction against the work. The sliding collar 3 is rigidly connected to the bolt 1 and moves in the bearing 4. At its other end the bolt 1 carries the bow 5 which surrounds the two contact devices and is provided with a micrometer screw 8, together with the graduated head 9 and pointer 10. By means of a small lever 11, which is supported against a nut 12 serving to tighten up the spring 2, the bolt can be drawn back from contact with the work. The whole device is mounted on a slide-rest 14, 15 which gives a motion parallel to and at right angles with the work.

At the commencement of grinding, the device may be set by the aid of the graduated head 9 and pointer 10, so as to give the interval S^1 corresponding to the desired coarse grinding, while the interval S^2 , corresponding to the desired fine grinding, can be set, if necessary, by means of the graduated head 13. In the course of grinding, as soon as the bolt 1 has traversed the adjusted distances successively, in a radial direction, and the work has consequently attained the desired dimensions after the coarse and fine grinding, the contacts 6, 7 touch one another and thus stop the feed motion of the grinding wheel.

Now what I claim and desire to secure by Letters Patent is the following:

1. In a device for automatically arresting a feed motion, the combination of a longitudinally movable bolt; a spring for normally holding said bolt in contact with the work; a micrometer screw; connections between said screw and said bolt; and an electrical contact adapted to be controlled by said spring through said connections, substantially as described.

2. In a device for automatically arresting a feed motion, the combination of a longitudinally movable bolt; a spring for normally holding said bolt in contact with the work; a micrometer screw, the axis of which is longitudinally adjustable; connections between said screw and said bolt; and an electrical contact, one member of which is rigid with said axis, adapted to be controlled by said spring through said connections and independently through the adjustment of said screw, substantially as described.

3. In a device for automatically arresting

- feed motions, the combination of a longitudinally movable bolt; a spring normally controlling the same; a micrometer screw connected to said bolt; means for adjusting said bolt longitudinally; an electrical contact controlled by said screw and adapted to be closed by said spring; and means permitting said bolt to be moved transversely, substantially as described. 5
- 10 4. In a device for automatically arresting feed motions, the combination of a longitudinally movable bolt; a spring normally controlling the same; means for adjusting the tension of said spring; a micrometer screw 15 connected to said bolt; means for adjusting said bolt longitudinally; an electrical contact controlled by said screw, one member of said contact being carried by said screw; said contact adapted to be closed by said spring, and 20 independently closed by said screw; and means permitting said bolt to be moved transversely, substantially as described. 25
5. In a device for automatically arresting feed motions, the combination of a bolt; a spring controlling the motion thereof; a mi-
- crometer screw; connections between said bolt and screw; an electrical contact adapted to be closed by said spring; a second electrical contact; and a second micrometer screw controlling the same, substantially as described. 30
6. In a device for automatically arresting feed motions, the combination of a bolt; a spring for moving the same longitudinally; means to adjust the tension of said spring; a micrometer screw; connections between 35 said bolt and said screw; a second micrometer screw; electrical contacting points carried by each of said screws; and a spring pressed element carrying electrical contacting points coöperating with said first mentioned points, substantially as described. 40

In testimony, that I claim the foregoing as my invention, I have signed my name in presence of two witnesses, this 5th day of November, 1908.

FRIEDRICH SCHWERD.
